Fig. 1.

Fig. 2.

The diagram illustrates a circuit for a magnetic switch assembly. At the top, a horizontal bar with a hatched pattern is supported by two springs, labeled 'S' and 'F'. Below this bar, a central vertical line connects to a junction point. From this junction, two lines branch out: one to the left and one to the right. The left branch contains a series of contacts labeled '1', '2', and '3'. The right branch contains a series of contacts labeled '1'', '2'', and '3''. These contact sets are arranged in a staggered pattern. A line from the rightmost contact '3'' leads to a switch component labeled '66'. Another line from this switch '66' leads to a switch labeled '45'. From switch '45', a line goes to a ground symbol (a circle with a vertical line). From the junction point where the lines from '1', '2', and '3' meet, a line goes down to a switch labeled '34'. This switch '34' is connected in series with a switch labeled '35'. A line from the junction of '34' and '35' goes to a switch labeled '62'. Below switch '62', there is a ground symbol. From the junction of '62' and '34', a line goes to a switch labeled '12'. From switch '12', a line goes to a ground symbol. From the junction of '12' and '34', a line goes to a switch labeled '14'. From switch '14', a line goes to a switch labeled '46'. From switch '46', a line goes to a switch labeled '47'. From switch '47', a line goes to a switch labeled '58'. From switch '58', a line goes to a switch labeled '52'. From switch '52', a line goes to a switch labeled '50'. From switch '50', a line goes to a switch labeled '48'. From switch '48', a line goes to a switch labeled '53'. From switch '53', a line goes to a switch labeled '67'. From switch '67', a line goes to a switch labeled '69'. From switch '69', a line goes to a switch labeled '70'. From switch '70', a line goes to a switch labeled '71'. From switch '71', a line goes to a switch labeled '72'. From switch '72', a line goes to a switch labeled '73'. From switch '73', a line goes to a ground symbol. A line from the junction of '1', '2', and '3' also connects to a switch labeled '36'. From switch '36', a line goes to a switch labeled '26'. From switch '26', a line goes to a switch labeled '16'. From switch '16', a line goes to a ground symbol.

UNIVERSAL IMPULSE UNIT

Harry E. Williams and Lyndon A. Durant,
Chicago, Ill.

Application March 3, 1941, Serial No. 381,456

5 Claims. (Cl. 177—380)

This invention relates to a universal impulse unit for game apparatuses or the like and has for its principal object the provision of an improved construction of this character which will be highly efficient in use and economical in manufacture.

Among the other objects of this invention is the provision of a combination and arrangement of parts arranged in an electric circuit under the control of various switch means any of which when operated will cause the new unit to function for the purpose of recording a number of impulses corresponding to the value of the particular switch operated.

Another object of the invention is to provide a universal impulse unit in which there is provided means for successively operating a plurality of control mechanisms by electrical means corresponding to a particular initial operating switch when the latter is operated.

Other objects will appear hereinafter as the invention is described in the specification and in view of the drawing in which:

Fig. 1 is an elevational view of the new unit;

Fig. 2 is a vertical sectional view of the same as seen along line 2—2 in Fig. 1; and

Fig. 3 is a schematic electrical wiring diagram with which the unit of Figs. 1 and 2 may be associated.

Heretofore in game apparatuses it has been the custom to operate score counters, free play mechanisms and their respective resetting units by means of individual control with each of said counters. This present invention contemplates the provision of an impulse control of an impulse switch so that the various counter and totalizer mechanisms may be operated from a central or local unit.

The new unit is indicated at 10 and consists of a mounting plate 11 upon which is fixedly mounted a motor 12 which is adapted to drivingly engage a train of gears 13 to effect rotatable movement to a main shaft 14. The shaft 14 is journaled for rotatable movement in a frame 15 carried by the mounting plate 11. Freely mounted coaxially on the shaft 14 is a disc 16 having a hub portion 17 which surrounds the shaft 14. A star wheel 18 is keyed to the shaft 14 by means of a set screw 19 for rotation with the shaft and has a plurality of teeth 20 formed on its peripheral edge (Fig. 1). A dog 21 is pivotally carried as at 22 on the disc 16 with its free end 23 bent at right angles to the lever 21 and this lateral extension 23 is normally urged into operative engagement with a tooth of the

star wheel 18 by means of a spring 24 having its opposite end anchored as at 25 on a pin carried by the disc 16.

The star wheel 18 and spring urged lever 21 provide a slip clutch for the disc 16 so that when the shaft 14 and wheel 18 are rotated the disc 16 will be rotated therewith.

A second disc 26 is arranged concentrically on disc 16 by means of stud screws 27 and is held in spaced relation with respect to the disc 16 by washers 28. The disc 26 is of a non-conductive material such as fibre or the like and has its peripheral edge 29 serrated to provide a plurality of notches 30. A resilient cam spring 31 is carried upon a bracket 32 mounted upon the plate 11, and this leaf spring 31 is disposed with its free end portion 33, which is provided with a V-shaped cam, normally bearing against the peripheral edge 29 of the disc 26, and adapted to intermittently move into the notches 30 as the disc 26 is rotated. A switch means 34 is also carried on the bracket 32 and has one leaf spring 35 thereof normally disposed in spaced relation with a stationary leaf spring 36 of the switch 34 by means of a stud 37 fixedly mounted to the free end of the leaf 35 and bearing against the resilient cam spring 31. The arrangement is such that each time the cam 33 is disposed in a notch 30 the leaf spring 35 will be urged into circuit-connecting condition with its corresponding leaf 36. The disc 16 has V-shaped notches 38 formed in its peripheral edge 39 to divide the latter into four equal segments for reasons to be hereinafter explained. A cam spring 40 is carried on a bracket 41 supported upon the plate 11 and has its free end provided with a V-shaped cam 42 normally bearing against the peripheral edge 39 of the disc 16. A leaf spring switch 43 is also carried on the bracket 41 adjacent the cam spring 40 and has its contacts 44 and 45 in closed contact position when the cam rides upon the periphery 39 of the disc 16 and the spring switch 45 is adapted to assume open circuit condition when the cam portion 42 is disposed in one of the notches 38.

The new unit is further provided with a brake means 46 and this brake means includes a solenoid coil 47 fixedly mounted on the plate 11 and has an armature 48 associated therewith. This brake means 46 is adapted to control the rotative movement of the disc 16, and to this end the disc 16 has formed therein a number of elongated openings 49 arranged with their long axis radial with respect to the disc 16 and corresponding in number to the notches formed in the pe-

ripheral edge 38 of the disc. The armature 48 has one end portion 50 reduced in diameter and extending through an insulated sleeve 51 carried by the plate 11, the free end 52 of the member 50 being guided for axial movement with respect to the coil 47 by a metal bracket 53 arranged on the plate 11. The portion 50 of the armature is provided with a washer 54 and a coil spring 55 disposed between the washer and the bracket 53 so as to urge the armature 48 toward the disc 16. The opposite end of the armature 48 is provided with a reduced finger 56 to provide a shoulder 57, the finger 56 being of a size to fit into the opening 49 formed in the disc 16 with the shoulder 57 bearing against the face of the disc and preventing further movement of the armature toward the disc. The free end of the reduced portion 50 of the armature 48 is disposed to contact with a leaf spring 58 supported on the bracket 53 with its free end positioned adjacent the end 52 of the armature and normally out of contact with the same.

In Fig. 3 there is shown a schematic electric wiring diagram which has been preferably, though not necessarily, found to be suitably adapted for the employment of our new unit. In this diagram there is schematically shown a ball playing surface 60 upon which are disposed ball objectives 61 in the form of ball operated switches, one of which is designated S to signify it as being a score switch. This switch S receives current from the main line 62 and is adapted when closed by the action of a ball to complete circuit to a conductor 63 whereby to energize a score relay 64 which is grounded through conductor 65 and the switch 45 on the unit 10. Energization of the relay 64 causes the closing of its respective contacts, No. 1 of which is a self-locking contact for holding the relay in circuit; No. 2 of which connects circuit from the line 62 through conductor 66 to the coil 47 of the brake 46; and No. 3 of which connects the stationary leaf spring 36 of switch 34 with the coil 67 of the score stepping mechanism.

Energization of the brake coil 47 as aforesaid will cause the finger 56 of the armature 48 to be withdrawn from the slot 49 in disc 16 to free the latter for rotative movement, and simultaneously therewith the end 52 of the armature will contact the leaf spring 58 to complete circuit to the winding of the motor 12 whereupon the latter will cause rotation of the train of gears 13 and shaft 14 and through the star 18 and lever 21 cause rotation of the discs 16 and 26. (Counterclockwise, Figs. 1 and 3.)

It will be noted that the notches 30 in the disc 26 are five to each segmental unit between the notches 38 on the disc 16. For this reason there will be five successive impulses through the switch 34 and at the fifth impulse the cam 42 will ride into the next successive notch 38 on the disc 16 thereby permitting the contacts 44 and 45 of the switch 43 to be separated to break circuit to the relay 64 deenergizing the latter and the coil 47 of the brake member 46 so that the spring 55 will urge the armature 48 into latching engagement with the notch 49 and lock the disc against further rotative movement. The five successive impulses upon the switch 34 will have transmitted five impulses to the coil 67 of the score stepping switch and thereby cause a recording at five points.

The switch 61 designated F is associated with a free play counter 70 and when the switch F is closed by the action of a ball it causes the ener-

gization of a relay 84 having relay contacts 1', 2', and 3' like unto the contacts numbered 1 to 3 inclusive on the score circuit. By energization of the relay 84 the brake coil 47 will be energized through contact 2' and the motor 12 will rotate the discs 16 and 26 to again cause a number of successive operations of the impulse switch 34 and this time the closing of the switch 34 will through the relay contact 3' connect circuit to the add coil 71 on the free play unit which actuates a unidirectional advancing pawl 71' to advance a ratchet 77 on the free play unit (clockwise, Fig. 3) to record a number of free plays corresponding to the number of impulses on the switch 34 by reason of the operation of the disc 26.

A pivotally mounted holding pawl 80 is spring urged into engagement with the ratchet 77 to hold the latter in successively advanced positions. Means for returning the ratchet 77 to initial or zero position comprises a rocker arm 81 pivotally mounted at 81' and having a resetting pawl 82 normally out of engagement with the ratchet 77 but adapted to move in engagement with the toothed peripheral edge thereof to return the ratchet 77 (counterclockwise) toward initial or zero position in step by step fashion. The rocker arm 81 is linked as at 83 to a subtracting solenoid 75 which when energized rocks the rocker arm 81 toward the ratchet 77 to cause the resetting pawl 82 to engage the periphery of the ratchet 77 as aforesaid and simultaneously to cause an abutment 84 on the rocker arm 81 to pivot the holding pawl 80, against the action of its spring, out of holding engagement with the ratchet 77 thus freeing the latter for counterclockwise movement by the resetting pawl 82.

In order to reset the free play recorder 70 there is provided a push button 72 arranged in the cabinet with which the unit is associated and this push button is adapted to close a switch 73 to initially energize a reset relay coil 74 having a holding contact 1'' and a contact 2'' for energizing the brake coil 47 and a relay contact 3'' for connecting the subtracting solenoid 75 in circuit with the impulse switch 34. In this regard it is to be noted that when the free play unit 70 is in zero position an insulated pin 76 carried on the ratchet 77 normally engages a leaf spring 78 to separate its contacting engagement with a corresponding leaf spring 79 thereby breaking the circuit to the ground of the free play reset coil 74. When the coil 71 has been energized and the mechanism 70 has been stepped up one or more steps, the extension 76 will have been moved away from the leaf spring 78 to allow the latter to make contact with the spring 79 and thereby ground the circuit to the coil 74. In this regard it is to be noted that the resetting of the mechanism 70 is in no way affected by the switch 45, the latter of which is not connected in the circuit to the free play reset relay coil 74 and for this reason when the ratchet 77 is in advanced position a plurality of steps the motor 12 will continue to rotate the discs 16 and 26 until the ratchet 77 is returned to initial position to break the circuit at leaf spring 78.

While the impulse unit described in our invention has been arranged in a game apparatus we do not desire to be bound to such an arrangement. This invention is capable of variations and modifications coming within the scope of our invention and we desire to protect ourselves as broadly as the disclosure will permit.

It will be noted that we have provided an im-

pulse unit which is universal to a number of different and separate operations all of which may be combined in one structure with which each unit is associated.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the scope of the appended claims.

Having thus described our invention, what we claim as new and desire to protect by Letters Patent is:

1. In an impulse control, a frame, a motor on said frame, a driven disc means, means for connecting said disc with said motor for driving operation by the latter, brake means including a reciprocable member, means for urging the latter into engagement with said disc, said disc having a serrated edge portion, switch means arranged to engage said edge portion and adapted to assume open and closed condition intermittently by reason of engagement with said serrated edge portion, and means for affecting said brake means for withdrawing said reciprocable member out of latching engagement with the disc and simultaneously effecting operation of said motor.

2. In an impulse control including a frame and a rotatable disc arranged for rotatable movement on the latter, motor means drivingly connected with said rotatable disc, notches formed on the periphery of said disc, switch means arranged to bear against the periphery of the disc to normally dispose the switch in closed condition and adapted to assume open condition when seated in a notch, slots formed in said disc, brake means including a reciprocable element, spring means normally urging said element toward said rotatable disc and into latching engagement with the slots formed therein, relay means having circuit connection through said switch means and adapted to connect circuit to said brake means to effect withdrawal of said reciprocable element from latching condition, switch means affected by the latter movement of said reciprocable element for effecting operation of said motor, and means for energizing said relay means.

3. In a device of the class described including a rotatable member having a peripheral edge portion, means comprising a control disc mounted to rotate with said rotatable member, stopping means spaced about the axis of rotation of said rotatable member, said disc having a serrated peripheral edge portion, control switch means operatively engaging said peripheral portion to normally dispose said switch in closed condition and adapted to assume open condition when said control switch engages one of the serrations, brake means including a brake member yieldably bearing against the rotatable member for stopping engagement with any of said stopping means, said brake means further including electrically operated means to move said brake mem-

ber from stopping engagement aforesaid, electric motor means drivingly connected with said rotatable member, notches formed in said rotatable member at intervals about its peripheral edge, cam switch means, connected in circuit with said electrically operated means and normally engaging the edge of said rotatable member to dispose the switch in closed circuit and adapted to assume opened circuit condition when aligned with one of said notches, switch means connecting said motor in circuit and arranged to be disposed in closed circuit condition by said brake member when the latter is moved from stopping engagement with said rotatable member, and means for effecting energization of said electrically operated means.

4. In a device of the class described, a mounting plate, drive means on said plate, a rotatable disc arranged on said plate for rotation by said drive means, said disc having a notched peripheral edge, switch means engaging said edge to normally dispose the same in closed circuit condition and adapted to assume open circuit condition when disposed in one of said notches, brake means including a reciprocable member and means for urging the same into latching engagement with said rotatable disc, electrically operated means connected in circuit with said switch means, a control disc mounted for rotation with said rotatable disc and having a serrated edged portion, impulse switch means operatively engaging said serrated edge portion and adapted to open and close intermittently corresponding to the number of serrations engaged by said impulse switch, a motor control switch arranged to be disposed in closed circuit condition by said reciprocable member, and means for initially energizing said electrically operated means to permit operation of said motor.

5. In a device of the class described, a mounting plate, drive means on said plate, a rotatable disc arranged on said plate for rotation by said drive means, said disc having a notched peripheral edge, switch means engaging said edge to normally dispose the same in closed circuit condition and adapted to assume open circuit condition when disposed in one of said notches, brake means including a reciprocable member and means for urging the same into latching engagement with said rotatable disc, electrically operated means connected in circuit with said switch means, a control disc mounted for rotation with said rotatable disc and having a serrated edged portion, impulse switch means operatively engaging said serrated edge portion and adapted to open and close intermittently corresponding to the number of serrations engaged by said impulse switch, a motor control switch arranged to be disposed in closed circuit condition by said reciprocable member, and means for initially energizing said electrically operated means to permit operation of said motor to effect operation of said impulse switch means a number of times as aforesaid.
